ELECTRICAL RECEPTACLE

Herbert J. Graham, Philadelphia, Pa., assignor
to Electric Service Supplies Company, Phila-
delphia, Pa., a corporation of Pennsylvania

Application April 25, 1928. Serial No. 272,729

6 Claims. (Cl. 173—356)

This invention relates to electric lamp sockets and the like and more particularly to improvements therein for effectually precluding that destructive arcing which takes place between the center contacts of the lamp and socket and at the socket terminals when the lamp socket is subjected to vibration and other shocks incidental to its use.

It has been found that in the usual type of lamp socket the tendency has been for the lamp to "back-out" or become loosened when the socket is subjected to undue vibrations, shocks or jars, this difficulty being especially noticeable in those instances where the lamp socket is used in connection with locomotive headlights. Continual loosening of the lamp within its socket soon results in an uncertain electrical contact between the center contacts of the lamp and socket with the consequence that a destructive and dangerous arcing condition is established between said center contacts. This same destructive arcing condition often arises at the socket terminals when the latter become loosened due to excessive vibration of the socket. Various expedients have been resorted to from time to time with a view to obviating these troubles, but none of them have been particularly successful. In certain cases the sockets were so designed that it became difficult to remove the lamp when it was desired to do so. In other cases, the socket constructions were not of sufficient strength and rigidity to meet the present strict requirements, while in still other cases their general use was prohibited because they were either too complicated or too expensive to manufacture.

It is accordingly among the principal objects of this invention to provide a lamp socket having means for securely gripping the base of a lamp to effectually prevent any tendency of the latter to either vibrate or become loosened in the socket, said means being simple and efficient in use at the same time that it is capable of being readily applied to the socket without impairing the strength and rigidity of the latter.

A still further object of the invention is the provision of a gripping device in association with a lamp socket, said device being so arranged with respect to said socket that the lamp base is firmly gripped immediately as it is threaded into the socket. By reason of this arrangement, it will be apparent that when the lamp base is threaded into the socket so that the center contacts thereof are in firm contact the base will be gripped at a point removed from its inner end, that is, at a point adjacent the lamp receiving end of the socket. In consequence of the fact that this gripping action takes place at the outer end of the socket, it becomes difficult, if not entirely impossible, for one to shift the lamp laterally with respect to the socket in order to obtain better

focusing thereof. This practice of obtaining better focus by shifting the lamp within its socket rather than by making an adjustment of the latter often results not only in injury to the lamp but in injury to the socket as well.

A still further object of this invention is the provision of a pair of spring-pressed devices for frictionally engaging opposite sides of a lamp base, these devices being so constructed as to afford a broad frictional engagement to be had against the thread of the lamp base, this engagement being such that the thread is reformed during the operation of threading the lamp base into its socket. The effect of this is to provide a much closer fit between the lamp base and its socket than is ordinarily had, yet the arrangement does not interfere with the ready withdrawal of the lamp from its socket when desired.

A still further object of the invention is the provision of means for facilitating the attachment of conducting wires to the socket, said attachment being effected not only more easily but in a more secure and permanent manner than has been possible heretofore. The usual practice has been to employ threaded binding terminals for clamping the wires in position, but this type of terminal has been found unsatisfactory where the socket is subjected to continuous vibration due to the fact that there is always the possibility of the terminals becoming loosened with the result that the wires either become disconnected entirely from the socket or else become so loosened as to establish that destructive arcing condition at the terminals which has been found so objectionable.

Other objects and objects relating to details of construction and assembly for effecting economies in the manufacture of the socket will appear more fully hereinafter.

The invention consists substantially in the construction, combination, location, and relative arrangement of parts, all as will be described more fully hereinafter, as shown in the accompanying drawing, and finally pointed out in the appended claims.

In the accompanying drawing:
Figure 1 is a side elevation of a lamp socket embodying the principles of this invention, a lamp being shown inserted within said socket;

Figure 2 is a top plan view of the socket;
Figure 3 is a bottom plan view of the socket;
Figures 4 and 5 are cross sectional views taken on the lines 4—4 and 5—5, respectively, of Figure 2.

Figure 6 is a perspective view showing one of the members for frictionally engaging the base of the lamp;

Figures 7 and 8 are perspective views of the terminal members of the socket;

Figure 9 is a fragmentary view of a lamp show-

ing the form which the thread of the lamp base takes when the latter is inserted into the socket; and

Figure 10 is an enlarged plan view of the left hand portion of the socket as shown in Figure 2.

Referring now more particularly to the drawing, it will be seen that the lamp socket embodying the principles of this invention comprises a main insulating body or casing 10 having a central recess or socket 11 within which is arranged to be received the threaded shell 12 constituting one of the contacts for the lamp 13. Projecting upwardly from and formed integrally with the bottom wall 14 of the casing 10 is a substantially U-shaped boss 15, the function of which is to divide the upper surface of said bottom wall into separate seats or depressions 16 and 17 for receiving, respectively, the contact terminals of the socket. The seat 16, which is that enclosed by said U-shaped boss 15, is of substantially rectangular form, while the seat 17, which is that embraced between the internal surface of the casing 10 and the external surface of said U-shaped boss 15, is of substantially U-shaped form. Transversely extending openings 18 and 19 are respectively provided in diametrically opposed sides of the casing 10, the opening 18 being in communication with the seat 16, while the opening 19 communicates with the seat 17. Communicating respectively with said transversely extending openings 18 and 19 are the openings 20 and 21 which extend vertically through the bottom wall 14 of the casing.

The threaded shell contact 12 within which the lamp base 22 is arranged to be threaded is of the form most clearly shown in Figures 4 and 5 wherein it will be seen that the bottom and one side thereof are slotted, as at 23, the construction of this shell being such that when it is positioned within the insulating casing 10 the upwardly projecting U-shaped boss 15 will project freely through the bottom of said shell. In other words, the arrangement is such that when the screw shell is positioned properly within its casing the bottom thereof will be in embracing relation with respect to said U-shaped boss.

For the purpose of electrically connecting a conducting wire to the threaded shell contact 12, there is employed a terminal member 24 of the form best shown in Figure 7. This terminal member, which comprises a slotted portion 25 corresponding in shape to the slotted portion of the screw shell 12, is provided with a depending lug 26 having a portion thereof struck out, as at 27, to form a loop through which the bared end of a conducting wire may be inserted. As appears most clearly in Figures 4 and 5, the terminal member 24 is arranged between the screw shell 12 and the bottom wall of the casing 10, the lug 26 thereof projecting downwardly toward the bottom of the socket such that access may be had thereto through the transverse opening 19. The terminal member 24 is provided with apertures 28, the bottoms of the casing 10 and the screw shell 12 being correspondingly apertured for the passage therethrough of the securing elements 29. Preferably these elements are in the form of rivets. If desired, and it is considered preferable, a reinforcing plate 30 may be inserted within the screw shell 12 such that it overlies the bottom thereof, the primary consideration being that all the parts be clamped firmly together with the terminal member 24 in good electrical contact with the base of the screw shell 12.

Arranged within the central seat or depression

16 is the central terminal member 31 of the form best shown in Fig. 8, this member being provided with a portion 32 presenting downwardly and toward the transverse opening 18, said portion terminating in a downwardly presenting lug 33 having a struck out portion 34 forming a loop through which the bared end of a second conducting wire may be passed. Access is had to the lug 33 through the transverse opening 18. Overlying the terminal member 31 is the center spring contact member 35, both of these members being firmly clamped together and to the bottom wall of the casing 10 by the securing element 36, preferably a rivet. The free end 37 of the contact member 35 is formed with a depression 38 arranged to seat over the headed end 39 of the rivet 36, the arrangement being such that when the lamp base is threaded into the socket to its full extent the headed end 39, being received within the depression 38, serves to effectually preclude any tendency for the free end of the center spring contact member to shift laterally out of contact with the center contact of the lamp base.

The conducting wires are permanently attached to the terminal members 24 and 31 of the socket by means of soldered connections effected after the bared ends of the wires have been inserted through the loops 27 and 34 of the terminal members. The openings 18 and 19 in the sides of the socket facilitate the necessary soldering operations. In this connection it is to be understood that while it is deemed preferable to provide soldered connections as herein described, any other form of permanent connection between the terminal members and the conducting wires may be utilized without departing from the general spirit of this invention. The arrangement just described not only provides for a strong and durable connection between each terminal member and its respective lamp contacting element, but it also affords a more permanent connection between each conducting wire and its respective terminal member, the result of which is that the possibility of these latter connections becoming loosened when the socket is subjected to continuous vibration is greatly minimized, if not entirely eliminated. Destructive arcing conditions at the socket terminals is thus obviated.

In order to eliminate the destructive arcing condition which often takes place between the center contacts of the lamp and socket when the latter is subjected to undue vibration, there is employed in association with the threaded shell contact 12 a pair of lamp base gripping members 40, one of which is shown in perspective in Figure 6. Each of these members 40 comprises a transversely curved spring plate 41 adapted for insertion between the internal surface of the casing 10 and the external surface of the shell contact 12. As appears most clearly in Fig. 4, two plates 41 are employed in diametrically opposed relation, and inasmuch as these plates are each of a transverse curvature less than that of the annular space within which they are inserted the plate must be flexed to a greater than their normal curvature, the resulting tendency being for the plates to assume their normal shape with the consequence that an inward pressure is exerted against the external surface of the shell contact 12. Secured adjacent the upper edge of each plate 41 and projecting outwardly from the concaved surface thereof is a nub 42, preferably of substantially semi-spherical shape, these nubs being arranged to project inwardly and toward

each other through suitable apertures 43 formed in opposite sides of the screw shell 12 so as to follow the threads thereof.

The nubs 42 project a sufficient distance 5 through the apertures 43 in the screw shell so as to afford a firm frictional engagement with the lamp base when the latter is threaded into the socket. In order to insure and obtain a broad frictional engagement between these nubs and 10 the lamp base, the former are of a diameter substantially equal to the pitch of the thread of the lamp base, the pressure which is exerted upon said nubs being sufficient to cause them to reform the lamp base thread to the exact external contour 15 of the nubs, the reformed lamp base thread being shown in Fig. 9. As appears most clearly in Figures 4 and 5, the nubs 42 are arranged adjacent the lamp receiving end of the screw shell 12 so that the lamp base is firmly gripped immediately that it is inserted into the socket, this gripping action continuing thereafter throughout substantially the entire extent of the thread convolution. In consequence of the fact that this gripping action takes place at the outer end of 20 the socket, it becomes impossible for the lamp to shift laterally or vibrate when it has been threaded into its socket, thereby insuring at all times a firm electrical connection between the center contacts of the lamp and socket. If desired, the socket casing 10 may be provided with 25 the vertically extending internal ribs 44 which serve as supplemental spacers between the screw shell 12 and the casing 10. Provided in the base of the socket are a pair of internally threaded 30 inserts 45 arranged to receive the ends of suitable securing elements (not shown), for securing the socket to a mounting member (also not shown).

It will be observed that in this particular socket the center spring contact 35 serves solely as 40 an element for electrically connecting the center contact of the lamp with the terminal member 31, it being unnecessary to depend upon its resiliency to prevent the lamp from "backing-out" 45 of its socket, this latter tendency being effectually precluded solely by the action of the lamp base gripping members 40. It will be further observed that the lamp socket as described is not only simple and inexpensive in construction but 50 it is also efficient, strong and durable in use.

It will be understood that various changes may be made from time to time without departing from the general spirit or principles of the invention, and it is accordingly intended to claim 55 the said invention broadly, as well as specifically, as indicated in the appended claims.

What is claimed as new and useful is:

1. In a lamp socket, in combination, an annular 60 contact shell having an aperture formed in the side and adjacent the lamp-receiving end thereof, a main body enclosing said shell, and a transversely flexed plate interposed between said shell and said body in the vicinity of said aperture, said plate having free ends extending laterally to either side of said aperture and engaging said body and said plate being provided with a projection extending through said aperture for resiliently engaging the base of a lamp inserted into said socket.

70 2. In a lamp socket, in combination, a threaded contact shell having an aperture formed in the

side and adjacent the lamp-receiving end thereof, an insulating casing enclosing said shell and provided with a plurality of internal vertically extending ribs for maintaining said shell and casing in spaced relation, a flexible plate arranged within the space formed between said shell and casing, the curvature of said plate being normally less than that of said casing such that the central portion thereof is resiliently urged against the external surface of said shell, and a projection carried by said plate and arranged to be resiliently urged through said aperture for frictionally engaging a lamp base inserted into said socket.

3. In a lamp socket, in combination, a threaded contact shell having oppositely disposed apertures formed in the upper portion of the thread convolution, an insulating casing surrounding said shell and maintained in spaced relation with respect thereto, a pair of opposed flexible members interposed between said shell and casing, the outer portions of each of said members being arranged in abutting relation against said casing such that the intermediate portion thereof is resiliently urged against said shell, and studs secured to said members and projecting through said apertures into the interior of said shell for engaging opposite sides of a lamp base inserted into said shell, the inner ends of said studs being each of a vertical cross-section of arcuate form and of a depth substantially equal to the pitch of a standard lamp base thread the vertical curvature of said means being of greater radius than the radius of the corresponding curvature of a standard lamp base thread.

4. In a lamp socket, in combination, a threaded contact shell having oppositely disposed apertures formed therethrough, and spring-pressed means projecting through said apertures for frictionally engaging opposite sides of a lamp base threaded into said shell, the vertical curvature of said means being of greater radius than the radius of the corresponding curvature of a standard lamp base thread the pressure applied to said means being from a point located exteriorly of the contact shell.

5. In a lamp socket, in combination, a threaded contact shell arranged to receive a threaded lamp base therein, and spring-pressed means projecting laterally through an aperture formed in the wall of said shell and into the path of said lamp base, the projecting end of said means being of a convex curvature less than the corresponding concave curvature of the thread of said lamp base whereby when the latter is threaded into said shell said thread is reformed to correspond to the curvature of said projecting end.

6. In a lamp socket, in combination, an insulating body member having an opening in the side wall thereof communicating with an opening in the bottom thereof, a lamp base contact member secured to said body member, a terminal element operatively associated with said contact member and having a struck-out portion forming a loop through which the bared end of a conducting wire may be inserted, said wire being insertable through said bottom opening and being accessible, for purposes of attachment to said terminal element, through said side wall opening.

HERBERT J. GRAHAM.
